UNITED STATES PATENT OFFICE

FAY D. KINNEY, OF WENHAM, MASSACHUSETTS, ASSIGNOR TO UNITED SHOE MACHINERY CORPORATION, OF PATERSON, NEW JERSEY, A CORPORATION OF NEW JERSEY

SHEET-SEPARATING APPARATUS

Application filed December 5, 1928. Serial No. 324,027.

This invention relates to apparatus for separating adhering sheets of material, a particularly useful application being found in connection with rubberized insoles for shoes, to which insoles are attached protective sheets of paper. In producing such work-pieces, a stack of sheets of insole-material, separated from one another by sheets of paper to prevent them from sticking together, are subjected to the action of a dieing-out apparatus, each die cutting simultaneously a plurality of insoles. Each of the cut insoles ordinarily bears upon its coated face a cut paper-piece, and this must be removed before the insole is utilized. This separating operation, as it has been performed manually, consumes considerable time, since the adhesion is strong, especially at the edges where the die forced the sheets together in making the cut. An object of my invention is to provide for the effective separation of adhering sheets much more speedily than when done by hand.

For the attainment of the above object, I provide, in a separating apparatus, a novel organization which has co-operating rotatable separating members, and means for retaining sheets in engagement with each member, said means being constructed and arranged to render the retention of the sheets effective during a portion only of the rotary movement of the member, the time of action best being variable. A separating force is thus exerted first, the sheets acted upon being thereafter released to allow their disposal. Preferably, there are co-operating separating members, furnished in the illustrated embodiment of the invention by rotatable rolls; and the retaining means, which is effective only about that portion of the periphery adjacent to the bite of the rolls, acts through openings, as by the creation of a suction therethrough. This draws the sheets apart, they following the surfaces of the rolls as they rotate. The separation having been thus started, at least one of the sheets may be further held in engagement with its roll, to elevate it and maintain the separation, as by a belt operating in contact with the roll beyond the field of action of the primary

retaining means. This secondary retaining means or belt I have shown as causing the delivery of the separated sheets at the incoming side of the rolls, where they may be received and removed by a conveyor. A conveyor at the opposite or outgoing side may receive the other separated sheet of each pair. Since the protective sheets are commonly coated with paraffin or some other wax, the separation is facilitated and the strength of the suction necessary is reduced, by heating the sheets in preparation for their presentation to the action of the suction. Whatever the separating means employed, I prefer to apply the heat by a conveyor-belt or belts, which deliver the sheets for separation. One of these conveyor-belts may also serve to receive sheets from the separating means, to remove them after their separation.

One of the several forms which my invention may assume is illustrated in the accompanying drawings,

Figure 1 being a vertical longitudinal section on the line I—I of Fig. 2;

Fig. 2, a full transverse section on the line II—II of Fig. 1; and

Fig. 3, an enlarged sectional detail through co-operating suction-openings of the two rolls.

In a base-frame 10 is journaled a lower separating roll 12, while an upper separating roll 14 is rotatably mounted in arms 16, 16 pivoted at 17 upon the base. The weight of the upper roll and its mounting may be utilized to produce proper engagement with the lower roll, their axes of rotation being substantially horizontal and lying, one above the other, in a vertical plane. Power may be applied to the shaft of the lower roll by a pulley 18 fast upon it, motion being transferred to the upper roll through spur-gearing 19. The rolls are each provided with sheet-retaining means, which may be identical for both. Extending longitudinally of each roll are series of peripheral suction-openings 20, these series being shown as parallel to the axis of rotation, and therefore to each other. Both the series and the openings in the series are relatively closely spaced, so that a substantially continuous suction effect may

be produced upon sheets passing between the rolls. The openings continue inward radially to meet passages 22, one for each series and extending along said series, parallel to the axis of their roll. For the respective rolls, all the passages are open at one extremity and closed at the other. The open ends of the passages, which are at the opposite extremities of the two rolls, co-operate with 5 a suction device consisting of a cylindrical head 24 surrounding the shaft of the associated roll and having a finished surface contacting with a like surface upon the adjacent end of the roll. A substantially air-tight 10 joint is furnished by forcing these surfaces together by a spring 26 for each of the lower and upper suction devices. The roll 12 appears as splined to move longitudinally of its shaft, the spring being interposed between it and nuts 28 threaded upon the shaft, these nuts permitting the force exerted by the spring to be adjusted. The roll 14 is secured against movement upon its shaft, and the other spring 26 acts upon the head 24, being 15 adjusted by nuts 28 similarly to the companion spring. The heads 24 are each movable along the corresponding roll-shaft, to permit them to make more perfect contact with the adjacent roll-surface, and are held 20 against rotation by pins 29 projecting respectively from the frame 10 and from one of the arms 16 and entering openings in the heads. Each pin is preferably made adjustable circumferentially of its roll by being secured in 25 a curved slot 31 formed in its supporting part. In each head, opening through the side co-operating with the roll, is a chamber 30, so located that it communicates with the passages 22 connecting with the openings 20 which are adjacent to the bite of the rolls at 30 the outgoing side. In the present instance, three series of the openings may be in simultaneous communication with either chamber. A suction is created in these chambers, and 35 therefore in the registering passages 22 and their openings 20, through connected conduits 32 leading to a pump (not illustrated). As adhering sheets pass between the rolls and come opposite the openings which are joined 40 to the suction-chambers 30, they are drawn apart and retained against the roll-surfaces as long as they are under the influence of the suction, being released to be separately disposed of after the passages leave the chambers. The times at which the suction acts 45 upon the sheets may be varied by altering the angular positions of the heads 24 under the control of the pins 29.

The force necessary to draw the sheets 50 apart may be much reduced by the application to them of heat before they come under the influence of the separating rolls. This is especially true when the protective paper-sheet carries a coating of such a wax as par- 55 affin. To heat the sheets, there is illustrated

in Fig. 1 a horizontally extending feed-conveyor 34 of the belt type, reaching rearwardly to a convenient distance, and at the end next to the separating rolls passing over guide-rolls 36 and 38. The roll 38 is of comparatively small diameter, permitting the conveyor 34 to be brought in close proximity to the separating rolls to facilitate the delivery of the work to them. Between the upper and lower runs of the conveyor 34, 70 and close to the former, is a heating table 40, which may be hollow, containing a chamber to which steam is delivered through a connection at 42. Heat is also preferably applied to the upper surface of the sheets by a belt 44 operating over a roll 46, which may be somewhat to the rear of the roll 38. Between the runs of the belt 44 is a heating table or chest 48, similar to that associated with the lower belt. Both the belts 34 and 44 may be formed of sheet-metal, this allowing them to most efficiently communicate the heat from the steam-tables to the work. Travel of the adjacent surfaces of the belts at the same speed toward the 75 separating rolls is produced by a sprocket-gearing 50 joining the shafts of the rolls 12 and 36, and a chain of spur-gearing 52 between the shafts of the rolls 36 and 46. The adhering sheets are introduced between the outer receiving ends of the conveyors, and are carried by these, for the proper distance, under the influence of the heat from the tables 40 and 48. This renders somewhat fluid the 80 coating of the paper-sheets, and also probably the rubberized coating of the insoles, reducing the adhesion between these sheets, so that, when they emerge from between the belts and are delivered to the rolls 12 and 14, they are in condition for relatively easy 85 separation.

At the outgoing side of the separating rolls 12 and 14, the insoles or other work-pieces are advanced over an apron 54 upon chain-conveyors 56, which carry the pieces freed from their protective sheets, away from the rolls and deliver them to a receptacle. The ends of the paper-sheets, carried upward for a time by the suction through the openings of the roll 14, enter a throat formed between the rising periphery of the roll and a retaining belt 58, which partially surrounds said roll. The belt 58 operates over a roll 60, journaled in the arms 16 above the roll 14, and over rolls 62 and 64, rotatable, respectively, near the center and at the lower extremities of opposite angular arms 66, 66 pivoted about the shaft of the roll 60. The roll 64 is of such relatively small diameter that it may be brought close to the bite of the separating rolls to receive the upturned end of the paper-sheets before they are fully released by the suction. The roll 62 is shown as adjustable in slots 67 in its arms, this permitting slack in the belt to be taken up. To advance the 100

belt 58, the roll 60 is rotated at substantially the peripheral speed of the roll 14 by sprocket-gearing 68 from the shaft of said roll. The paper-sheets having been received 5 between the belt 58 and roll 14, they are conducted upwardly away from the insoles upon the conveyor 56 until they reach the top of the roll. Here they are removed by a chute 70, which directs them upon the 10 upper run of the heating belt 44. This is traveling rearwardly, and conducts the paper-sheets to a point at which they may be collected.

To briefly outline the general operation of 15 the apparatus, adhering sheets, such as insoles S with protective pieces s of paraffin paper, are fed one by one between the belts 34 and 44, with the protective sheets uppermost. These belts convey the pieces along 20 the heating tables 40 and 48, bringing both sheets to such a temperature that much of their adhesiveness is destroyed. The heating belts deliver the sheets prepared for separation between the rolls 12 and 14. When 25 the forward ends emerge from between the rolls, both sheets come under the influence of the suction through the chambers 30 and the passages 22 and openings 20 at that time connected with the chambers. The insole 30 is thus temporarily retained in contact with the roll 12, and the paper-sheet with the roll 14. Just as the insole is freed from the suction by the passage of the openings 20 beyond the chamber 30, it is received upon the 35 apron 54, where it is held by its weight against following the paper-sheet. The latter, when relieved from the suction, has entered the throat between the belt 58 and the roll 14, and its travel consequently continues 40 upwardly in engagement with the roll and belt until, reaching the end of the latter, it falls upon the upper run of the conveyor 44 and is delivered at the opposite side of the machine from the insoles.

45 Having described my invention, what I claim as new and desire to secure by Letters Patent of the United States is:

1. In a sheet-separating apparatus, co-operating rotatable separating members, means 50 for retaining adhering sheets in engagement with each member, said means being constructed and arranged to render the retention of the sheets effective during a portion only of the rotary movement of the members, and means associated with one of the members only for further retaining the sheets in engagement with it.

55 2. In a sheet-separating apparatus, co-operating rotatable separating rolls each provided with openings, sheet-retaining means associated with the openings and acting at points opposite each other on said sheets, and sheet-retaining means associated with a roll beyond said openings.

60 3. In a sheet-separating apparatus, co-op-

erating rotatable separating rolls each provided with openings, sheet-retaining means associated with the openings and effective only adjacent to the bite of the rolls, and sheet-retaining means associated with said 70 openings at a point removed from the bite of the rolls.

4. In a sheet-separating apparatus, a rotatable separating roll provided with openings, means for creating a suction through 75 the openings, said suction means being arranged to cause the roll to elevate separated sheets, and means for holding sheets against the ascending surface of the roll.

5. In a sheet-separating apparatus, a pair 80 of co-operating rotatable separating rolls each provided with openings, and means for creating a suction through the openings, said suction being effective only adjacent to the bite of the rolls.

6. In a sheet-separating apparatus, a pair 85 of rotatable separating rolls provided with openings in their peripheries, a suction-head co-operating with each roll and fixed relatively to its rotation, said head being arranged to create a suction through the roll-openings as they pass it, and retaining means for the sheets after they pass from the influence of the head, said retaining means contacting with one of the rolls.

90 7. In an apparatus for separating rubberized insoles and protective paper-sheets, a pair of co-operating rotatable separating rolls, between which adhering insoles and sheets are passed, each provided with series 95 of openings in its periphery, a passage connecting the openings of each series, a head co-operating with an end of each roll and having a chamber into registration with which the passages revolve, a suction-conduit connected to each chamber, and a belt contacting with one of the rolls over the passages after they have left the chamber.

100 8. In a sheet-separating apparatus, a rotatable separating roll provided with sheet-retaining means effective about a portion only of the periphery of the roll, and a belt 105 extending in contact with the roll about its periphery beyond the field of action of the retaining means and arranged to direct separated sheets over the surface of the roll.

110 9. In a sheet-separating apparatus, a rotatable separating roll provided with sheet-retaining means effective about a portion only of the periphery of the roll, a belt operating 115 in contact with the roll beyond the field of action of the retaining means, and a conveyor to which the sheets are delivered by the belt and roll.

120 10. In a sheet-operating apparatus, rotatable upper and lower separating rolls each provided with retaining means effective only adjacent to the bite of the rolls, and means for directing separated sheets over the top of 125 the upper roll.

11. In a sheet-separating apparatus, rotatable upper and lower separating rolls each provided with retaining means effective only adjacent to the bite of the rolls, means for directing separated sheets over the top of the upper roll, and a conveyor receiving said sheets at the incoming side of the rolls.
12. In a sheet-separating apparatus, rotatable upper and lower separating rolls each provided with retaining means effective only adjacent to the bite of the rolls, means for directing separated sheets over the top of the upper roll, and conveyors at the opposite sides of the rolls to receive the sheets from the upper and lower rolls respectively.
13. In a sheet-separating apparatus, a rotatable separating roll provided with openings, means for creating a suction through the openings, means for presenting sheets to the roll-openings, and means for heating the sheets in preparation for their presentation to the action of the suction.
14. In a sheet-separating apparatus, a pair of co-operating rotatable separating rolls each provided with openings, means for creating a suction through the openings of each roll, and means for heating opposite sides of the sheets in preparation for their co-operation with the openings.
15. In a sheet-separating apparatus, sheet-separating means, a conveyor delivering to the separating means, and means for heating the conveyor.
16. In a sheet-separating apparatus, a pair of rotatable separating rolls, a conveyor-belt delivering sheets between the rolls, and means for heating the belt.
17. In an apparatus for separating rubberized insoles and adhering sheets of paraffin-paper, sheet-separating means, adjacent conveyor-belts arranged to receive sheets between them and to deliver to the separating means, and means for heating each belt.
18. In a sheet-separating apparatus, a pair of rotatable separating rolls, a conveyor-belt delivering sheets between the rolls, and a heating chamber situated between the upper and lower runs of the conveyor-belt.
19. In a sheet-separating apparatus, sheet-separating means, a conveyor delivering to the separating means, and means for heating the conveyor, the separating means being arranged to deliver separated sheets to the conveyor.
20. In a sheet-separating apparatus, rotatable upper and lower separating rolls each provided with retaining means effective only adjacent to the bite of the rolls, means for directing separated sheets over the top of the upper roll, a conveyor receiving said sheets at the incoming side of the rolls, and means for heating the conveyor.

In testimony whereof I have signed my name to this specification.

65 FAY D. KINNEY.
